INVENTOR

16 Morris Miller
BY C. P. Goepel
his ATTORNEY

UNITED STATES PATENT OFFICE

MORRIS MILLER, OF EAST ORANGE, NEW JERSEY, ASSIGNOR TO SIMON MILLER & CO., OF NEWARK, NEW JERSEY, A COPARTNERSHIP COMPOSED OF MORRIS MILLER AND EMANUEL MILLER

BRACELET CLASP

Application filed May 3, 1928. Serial No. 274,768.

This invention relates to improvements in a bracelet clasp for ornamental use; especially bracelets to be worn upon the wrist as an article of jewelry.

5 An object of the invention is to provide a bracelet clasp of such construction that the links thereof can be permanently connected to one another and yet permit the bracelet to be enlarged so that it can be slipped over 10 the hand upon the wearer's wrist and then shortened to keep it in position.

The nature and advantages of the invention are fully set forth in the following description taken with the accompanying drawings, 15 whereon a preferred embodiment of the invention is illustrated. This disclosure however, is explanatory only, and I may vary the shape, size and arrangement of the parts without exceeding the scope and principle of 20 the invention as defined in the appended claims.

On the drawings,—

Figure 1 is a view of part of a bracelet according to my invention with the extensible 25 parts shortened;

Fig. 2 is a similar view showing the same parts of a bracelet about to be extended to make the bracelet larger;

Fig. 3 is a bottom view of the bracelet with 30 its extensible parts in fully extended position;

Fig. 4 is a section on the line 4—4 of Fig. 3; Fig. 5 is a section on the line 5—5 of Fig. 3;

Fig. 6 is a section on the line 6—6 of Fig. 3;

35 Fig. 7 is a section on the line 7—7 of Fig. 3;

Fig. 8 is a cross section on the line 8—8 of Fig. 3;

Fig. 9 is a similar section on the line 9—9 of Fig. 3, and

40 Fig. 10 is a section on the line 10—10 of Fig. 3.

The same numerals identify the same parts throughout.

The bracelet is made up of a number of

45 short links 1 secured together by means of pivot pins 2 and these links may be of any desired construction. Enough of the links 1 will be included to make a bracelet of the desired length, all joined together and the 50 terminal links 1 will be united by larger links

indicated at 3, 4 and 5 which can be extended to make the bracelet bigger as shown in Fig. 3 or folded together as shown in Fig. 1.

For this purpose, the links 3, 4 and 5 are so designed that they have interfitting 55 engagement with one another. The link 3 has the form of an inverted trough; the link 4 consists of two strips perforated at their ends to be pivoted to the link 3 and the link 5; and the link 5 may be in the form of a closed 60 tube which is rectangular in shape. These three links, 5, 4 and 3 are illustrated in cross section on Figs. 8, 9 and 10 respectively. Thus, all of the links 1, 3, 4 and 5 are pinned 65 together and the bracelet is put on by making it larger and then shortening it to be worn around the wrist; and to remove it the links 3, 4 and 5 need only be distended. Hence, no catch is required.

The link 3 having the form of an inverted 70 trough is provided with a top 6 and sides 7 with one end thereof closed as indicated at 8. This end may be cut along the sides and then punched or stamped out to provide an open ended hollow projection 9 to serve as a bearing 75

for the pin 2 which connects it to the adjacent link 1. All of the pivot pins 2 may be tubular with their ends expanded to keep them in place. The sides of the adjacent link 1 may be rounded as indicated at 10 and the ends of the sides 7 of the link 3 may be

recessed to form seats as at 11 to match with the rounded ends 10 of the link 1. Each of the links 1 may be shaped in cross section so as to be somewhat similar to the link 3 and across the bottoms of these links may be connecting bars 12. At the opposite end of the link 1 joined to the link 3, are perforated projections 13 to enable it to be united by a pivot 80

pin 2 to the adjacent link. This adjacent link 90 may likewise have its ends rounded and the ends of said link 1 which are adjacent the projections 13 may also be recessed in the same way as the sides of the link 3.

The opposite end of the link 3 will be open 95 as shown at 14 and the sides thereof may also be recessed as shown at 11, and the two parts of the link 4 will enter the open end of the link 3 and be united thereto by pivot pins 15 which may be eyelet rivets. These rivets may 100

receive in their outer ends, knobs 16 preferably held in place by solder to add to the ornamental appearance of the bracelet.

At their opposite ends, the two parts of the link 4 will be pivotally united to the link 5 by means of pin 2. This link 5 comprises sides 17 and a top and bottom 18, and the sides 17 are extended somewhat and rounded as indicated at 19 where they are 10 united to the link 4. At the opposite end, the top of this link may be extended and bent to form a tubular bearing 20 so that it can be joined by a pivot pin 2 to the adjacent link 1, the bearing 20 being received between the 15 rounded ends 10 of the sides of this link 1.

All of the links 1, 3 and 5 may be curved somewhat and when the links 3, 4 and 5 are to be folded into one another to shorten the bracelet, the two parts of the link 4 are first 20 caused to enter the link 3 and be housed thereby; passing into this link through the open bottom. Then the tubular link 5 follows and both links 4 and 5 are completely enveloped by the link 3; one end of the link 25 5 then projecting from the open end 14 of the link 3 and being there attached to the adjacent link 1. The bracelet then has the form of a complete loop encircling the wrist snugly instead of having two ends to be joined 30 by a catch and can be removed by enlarging it merely by taking hold of the two small knobs 16 and pulling upward to get the links 3, 4 and 5 in a position to be distended as indicated on Fig. 3. The curvature of the link 35 3 is such that the outer surface of the bottom of this trough-shaped link, that is, the part or surface which will be uppermost and exposed when the bracelet is worn, is convex.

The construction is thus quite simple, while 40 at the same time the parts are securely united and there is no liability of the bracelet getting out of order.

I claim:

1. A clasp for a bracelet comprising a plurality of links pivotally connected together, one of said links having the form of an inverted trough with one end closed and a bearing at said end for a pivot pin to enable it to be connected to one end of the bracelet, 45 the other end of said trough shaped link being open, another of said extensible links having the form of a pair of strips which enter the open end of the trough shaped link and are pivotally united thereto, and a third 50 extensible link having the form of a rectangular tube, the end of which is received between the two strips of the second-named extensible link and is pinned thereto, the opposite end of the tube shaped link being pinned 55 to the opposite end of the bracelet, the extensible links being adapted to be folded together so that the strips of the second link are received into the trough shaped link along the sides thereof and the tube shaped link is 60 housed in said trough between the strips of 65

the second named link, the trough shaped link having knobs adjacent its open end to enable the trough shaped link to be pulled preparatory to distending the links and enlarging the bracelet.

2. In a clasp for a bracelet, consisting of connected links adapted to be extended to enlarge a bracelet, one of the links comprising a housing having spaced parallel side members, a second link in the form of a rectangular tube, two parallel oppositely disposed strip members, pivots connecting the strip members at one end with one end of the corresponding side members and at the inside faces thereof, a pin passing through the opposite ends of the strip members with one end of the tube fitted between the strip members, and knobs associated with said pivots, extending laterally beyond the side members and adapted to be grasped in operating the connecting links.

3. In a clasp for a bracelet, a box-like link having a protruding bearing connection at one end with the bracelet, a pair of parallel oppositely disposed strip members embracing at one end the opposite end of the box-like link and pinned thereto for pivotal movement, a housing including parallel oppositely disposed side members having seats in the end edges thereof, an individual pivot connecting the opposite end of each of the strip members with the corresponding side member adjacent the end edge seat thereof, thereby leaving between the strip members an unobstructed space, said strip members being foldable in the housing between the side members and said box-like link being foldable between the strip members to occupy said unobstructed space and permit said bearing connection to be received in said end edge seats.

In testimony that I claim the foregoing as my invention, I have signed my name hereto.

MORRIS MILLER.
